POUL ARNE SCOTT IVERSEN, OF COPENHAGEN, DENMARK, ASSIGNOR TO AXEL MAX
ALEXIS VON KAUFFMAN, OF COPENHAGEN, DENMARK

DEVICE FOR CONVERTING A RECIPROCATING OR OSCILLATING MOTION INTO A ROTARY MOTION

Application filed April 5, 1929, Serial No. 352,707, and in Germany December 22, 1928.

It is known to be old to convert a reciprocating or oscillating motion into a rotary motion by means of ratchet pawls. Such pawls pivotally attached to the reciprocating member are usually pressed against the ratchet wheel by gravity or spring action. In many cases, however, it is impossible to secure proper working of the movable pawls, especially when the members concerned have 10 to work at places where they are exposed to considerable squirting with water and dirt, for instance in connection with carriage brakes and where consequently there is great danger of the pawls becoming fixed, by rusting, in a position in which they cannot any longer reach the teeth of the pawl wheel, or of the pawls becoming caught by dried dirt, so that the intended action is not realized.

This drawback is removed by the present 20 invention in that the rotary motion is effected by means of projecting lugs or teeth fixed on the reciprocating or oscillating member, the said teeth engaging corresponding projecting lugs or teeth on the rotary member, and 25 the fixed teeth being spaced so far from one another in the direction of the motion that they only in case of sufficiently large motion come into engagement with the rotating teeth.

30 The novel device based upon this principal idea is illustrated on the drawing showing by way of example two different constructions. Both constructions relate to devices for automatic adjustment of carriage brakes, 35 but the invention may also be applied to many other purposes, or may easily be used for such purposes in similar manner or when slightly modified.

Fig. 1 shows a lever according to the invention built into the brake rods, in side elevation, in the position of repose.

Fig. 2 the lever, partly in section, in the braking position, and

Fig. 3 shows the lever in front elevation.

45 Figs. 4 to 11 show, in eight different positions, the lever head constituting the novel device.

Fig. 12 shows an inside view of an internal cheek brake with the brake drum removed, 50 and

Fig. 13 the adjusting device forming in this embodiment the novel arrangement according to the invention.

On an oscillatory shaft 1, operated in known manner for instance by the not shown 55 pedal lever, there is attached a lever 2. This lever supports at its free end a rotatably journaled bolt 3 fitted with a hole or bore 4. Through this hole one of the brake rods 5 is passing, and the rod is secured against withdrawal from the bore 4 by means of a nut 6. The braking device is tightened by rotation of the nut 6. All these details correspond to the usual arrangement, and do not constitute the object of the present invention. The 60 novel feature, on the other hand, is the device serving to adjust the nut 6 automatically.

The free end of the lever 2 is formed as a head consisting of two side plates 7 supporting each on the inside a lug or tooth 8 and 9. 70 On the nut 6 corresponding teeth or projections 10 are provided on which the teeth 8 and 9 can engage as further described in the following.

The device acts in the following manner: 75

When the brake is correctly adjusted the lever 2 will only perform relatively small angular motions during the braking operation, so that the tooth 9, in the position of repose illustrated in Fig. 4, cannot come into engagement with the teeth 10. But when owing to the wear of the brake lining in the course of time the angular motion of the lever 2 becomes greater than the tooth 9 will finally, as shown in Figs. 5 and 6, come into engagement with one of the teeth 10, and will therefore rotate the nut 6 correspondingly. During the subsequent return motion of the lever 2 into the position of repose the tooth 8 will come into engagement with a now further rotated tooth 10 (Fig. 7) and will turn this tooth further on, until finally the position shown in Fig. 4 is once more reached, the nut 6 however being now turned one tooth 10 forward. By this adjustment 85 the angular motions of the lever 2 will again become smaller, so that the nut 6 will now remain stationary in the new position, until a new wear has taken place, and the procedure repeats itself.

It appears, from this manner of operation that the nut 6 must be fitted with an uneven number of teeth.

But the adjusting rotation of the nut 6 will not in all cases be effected so easily as described above, for it may happen, as shown in Fig. 8, that a tooth 10 places itself with its point directly opposite the front edge of the tooth 8, whereby any forward motion of the tooth 8 becomes impossible, unless the parts 8 and 6 be movable relatively to one another, i. e. transversely relatively to the direction of motion of the fixed teeth. In the present construction this object is attained by the bolt 3 being laterally movable in the head 7, so that the forward motion of the tooth 8, as it appears from Fig. 9, produces a lateral displacement of the bolt 3, the rod 5 and the nut 6. Owing to the subsequent motion of the tooth 9 the nut 6 will again be moved into the central position, as shown in Figs. 10 and 11.

It follows from this that on account of the fixed arrangement of the teeth 8 and 9 the here described device will never be set out of order by rust or accumulation of dirt, so that the inventor has succeeded, by very simple means, in securing the automatic readjustment even during difficult conditions.

The details underlying the invention appear from the illustrations according to Figs. 4 to 11, but still another embodiment will be further described.

Figs. 12 and 13 show a brake consisting of two brake cheeks 11 and 12. The cheeks are pivoted in known manner about fixed pins 13 and 14, and are operated in known manner by a toggle member 16 disposed in known manner between bearing surfaces 15 at the free ends of the brake cheeks. The toggle member 16 is here disposed on a rectangular shaft 17 and supports beyond the free ends of the brake cheeks 11 and 12 two discs 18 acting here as a ratchet head. The bearing surfaces 15 on the front sides of the brake cheeks 11 and 12 are further formed as adjusting screws 19 and 20 screwed into the ends of the cheeks. These screws are provided with heads 22 fitted with teeth 21. The inner faces of the discs 18 are fitted with teeth or pins 23 which are not visible in Fig. 13.

In the same manner as for the previously described construction, as long as the brake is in order, the angular motion of the toggle member 16 cannot be sufficient for the teeth 23 to come into engagement with the teeth 21. But when wear takes place then this angular motion will become greater, and the teeth 23 (it may be mentioned for the sake of clearness that four such teeth are provided in the present construction, viz. two on each disc 18) will rotate the screws 19 and 20 in the same manner as described above, and will thereby cause the bearing surfaces to be readjusted. The necessary lateral motion can here be attained in simple manner, either by the toggle

member 16 being adapted to slide together with the corresponding discs 18 on the shaft 17, or by the parts 16 and 18 being rigidly connected to the shaft 17 and preferably made in one with the latter, while the shaft 17 is free to slide in its bearings.

What I claim as new is:

1. Adjusting device comprising a rotary adjusting member fitted with teeth and a reciprocating member fitted with fixed projecting lugs adapted to engage the said teeth, the distance between the said lugs, measured in the direction of the motion, being so great that the lugs can only engage the teeth on the adjusting member when the motion exceeds a certain limit.

2. Adjusting device comprising a rotary adjusting member fitted with teeth, and a reciprocating member fitted with fixed projecting lugs adapted to engage the said teeth, the said adjusting member and lugs being relatively movable in lateral direction at right angles to the motion of the fixed lugs.

3. Adjusting device comprising a rotary adjusting member fitted with teeth, two parallel plates, a member reciprocating in the direction of the said plates, a plate on each side of the adjusting member, and a fixed projecting lug on each of the moving plates, the said lugs co-operating with the teeth on the adjusting member and said adjusting member and the fixed lugs being relatively movable in a direction perpendicular to the plates.

In testimony whereof I affix my signature.

POUL ARNE SCOTT IVERSEN.
